Atty.*

UNITED STATES PATENT OFFICE.

SAMUEL ORKIN, OF ARLINGTON, MASSACHUSETTS.

DESIGN FOR A CHILD'S TOY.

54,765.

Specification for Design.

Patented Mar. 23, 1920.

Application filed September 26, 1919. Serial No. 328,077. Term of patent 14 years.

To all whom it may concern:

Be it known that I, SAMUEL ORKIN, a citizen of the United States, residing at Arlington, in the county of Middlesex and State of Massachusetts, have invented a new, original, and ornamental Design for a Child's Toy, of which the following is a specification, reference being had to the accompanying drawing, forming part thereof.

The figure is an elevation of a child's toy showing my new design.

I claim:

The ornamental design for a child's toy as shown.

SAMUEL ORKIN.

Witnesses:

NATHAN C. LOMBARD,
WALTER E. LOMBARD.
